UNITED STATES PATENT OFFICE

2,430,374

ELECTROLYTIC ALKALI HALOGEN CELL

Kenneth E. Stuart, Niagara Falls, N. Y., assignor
to Hooker Electrochemical Company, Niagara
Falls, N. Y., a corporation of New York

Application August 23, 1945, Serial No. 612,161

2 Claims. (Cl. 204—266)

1 My invention relates more particularly to an improvement upon the cell disclosed in Patent No. 1,866,065, granted to me July 5, 1932. One object of my invention is to provide a non-conducting member separating and forming liquid tight joints with the outer metal retaining wall structure of the cathode assembly and the flat metal plate to which the anodic electrodes are conductively affixed, when this plate constitutes a closure member of the cell. Another object of my invention is to protect this plate against electrolysis which would otherwise result from accidental minor leaks past said joints, when the plate constitutes the bottom closure member of the cell.

Referring to the drawings:

Fig. 1 is a sectional elevation through a cell of the type disclosed in the patent referred to, showing the construction of the cathode assembly and bottom closure member, and of the non-conducting separating member.

Fig. 2 is a sectional detail of a portion of cathodic outer metal retaining wall, the bottom closure member and the non-conducting member, to an enlarged scale.

Fig. 3 is a plan view of the non-conducting member by itself, to a reduced scale.

Fig. 4 is a side elevation of the non-conducting member by itself, partly in section, to the scale of Fig. 3.

Fig. 5 is an end elevation of the non-conducting member by itself, partly in section, to the same scale.

Fig. 6 is a sectional detail of a portion of the cathodic outer metal retaining wall, bottom closure member and non-conducting member separating the two, all of modified construction, to the scale of Fig. 2.

Fig. 7 is a plan view of a corner of the non-conducting member constructed in accordance with the detail of Fig. 6, but to the scale of Figs. 3 to 5.

Fig. 8 is a sectional detail of the bottom closure member and non-conducting member illustrated in Fig. 6, but adapted to a modified type of cathodic outer metal retaining wall.

Referring to Figs. 1 to 5:

Element 1 is a gas collecting cover member of halogen-resistant, non-conducting material, such as concrete, provided with exit 25 for the halogen gas. Element 2 is the cathode assembly, comprising outer retaining wall 3, provided with exit 26 for hydrogen and effluent pipe 27 for caustic alkali solution, foraminous cathodic electrodes 4, 4 adapted to be covered with asbestos diaphragm

5 material and to alternate with anodic electrodes 5, 5 which are in the form of flat blades of halogen-resistant conducting material, such as graphite. Anodic electrodes 5 project upwardly from conductive contact with plate 6, which forms the bottom member of the cell, the lower ends of electrodes 5 being preferably embedded in slabs of lead 7, 7 bonded to plate 6. Plate 6 is stiffened by ribs 29, which in turn rest upon insulators 30.

10 Brine is supplied to the inner compartment of the cell, to serve as electrolyte therein, by means of a tubular controlling device, not shown, in accordance with U. S. Patent No. 2,183,299, granted to me December 12, 1939. Element 28 is an electrolyte level indicating device, of the type in which the pressure built up by gas, in this case chlorine, trapped in a chamber having an open downwardly directed mouth, is indicated 15 by a manometer, thus giving a measure of the submergence of the mouth.

20 Direct electric current is supplied to the cell from a source not shown, through bus bars 25, 26. Resting upon plate 6 and conforming with the 25 exterior shape of the cell, is a flat frame 8, of non-conducting material, such as slate, concrete, a composition of asbestos fiber and cement, or other equivalent material, but in the drawings shown as constructed of wood. Frame 8 supports cathode assembly 2 and constitutes the non-conducting member referred to above.

25 Wall 3 is outwardly flanged at 9 and 10, as will be seen in Figs. 1 and 2, and the joint between flange 10 and frame 8 is rendered liquid tight by flexible gasket 11, of circular cross section, which I shall refer to as a "rope-type" gasket, in accordance with Patent No. 2,208,778, granted to me July 23, 1940. Gasket 11 is housed in a 30 groove 12 formed in the upper surface of frame 8, but presents a rounded surface to flange 10, which surface becomes flattened by pressure of the flange, as illustrated in the figures. This type of gasket requires that the frame be well filleted at its corners, as shown in Fig. 3. In the 35 construction of Figs. 1 and 2, in which the flange of wall 3 is outwardly directed, frame 8 may extend to the outer edge of the flange, in which case frame 8 is preferably formed of four side pieces and four corner blocks 13, as clearly indicated in Fig. 3, the side pieces and corner blocks being secured together by straps 14 and bolts 15. The joint between frame 8 and plate 6 is rendered 40 liquid tight by gasket 16, which is similar to gasket 11 and similarly housed in groove 17, formed in 45 the lower surface of frame 8. Frame 8 is, how-

ever, secured to plate 6 by bolts 18, and adapted to remain in position when cover 1 and cathode assembly 2 are removed.

Lead slabs 7, in which the lower ends of anodic electrodes 5 are embedded, are formed by pouring molten lead into the pans formed by plate 6 and fins 19. The space between electrodes 5, lead slabs 7, fins 19, plate 6, gasket 16 and frame 8 is sealed by pouring in molten bitumen, forming layer 20, which extends between electrodes 5 and completely covers and protects the metallic surfaces associated with the anode assembly. Layer 20 is preferably carried upward around its edges so as to cover the upper inner edge of frame 8 and over the upper surface of frame 8 as far as gasket 11. Frame 8 may have been previously rendered water-resistant by impregnation with a water repellent oil, such as linseed oil or a hydrocarbon drying oil; but in any case it is desirable to protect frame 8 as far as possible by carrying layer 20 over it to gasket 11. The material of layer 20 is plastic, even when cold, and will not prevent flange 10 from seating itself firmly upon gasket 11.

In Fig. 6 there is illustrated a modified structure in which the flanges 21 of cathodic retaining wall 3 are inwardly directed. In this case the flanges may be integral with the wall as before, but in the figure are shown as separate pieces welded thereto. One object of this construction is to economize floor space occupied by the cell. A comparison of Figs. 2 and 6 will show at a glance that by the construction of Fig. 6 there is a considerable reduction in the outer dimensions of the cell. This is accomplished, however, at the expense of the lateral space available for the sides of the frame, which is indicated at 22, and which in Fig. 6 constitutes the non-conducting member. Owing to the reduced width of frame 22 as compared with frame 8, the corners may be formed by sawing, steaming and bending, as illustrated in Fig. 7. In this case, since there is no space outside gasket 16 for the holding down bolts, a lag screw 23 is used, and this is placed inside of gasket 16.

In Fig. 6 there is also illustrated another feature of considerable importance, namely drip rim 24, formed along the outer face of frame 22 and extending downwardly around, outside of and below the edge of plate 6, as clearly illustrated in the figure. The purpose of drip rim 24 is as follows: In an alkali halogen cell, the metal parts of the cathode assembly, if of iron, are unaffected by electrolysis. However, plate 6, and all metal parts associated with it, are anodic. There is no known metal but platinum which will withstand nascent halogens. If iron be exposed to anodic conditions in an electrolytic chlorine cell, the chlorine combines with it as fast as withdrawn from the electrolyte. No chlorine whatsoever is liberated upon the iron surface, but all the chlorine appears as ferric chloride. Since this is very soluble, under these conditions the iron itself melts away almost as if it were itself soluble. Any accidental minor leak past gaskets 11 or 16 will therefore have a serious destructive effect upon the edge of plate 6, and in a very short time. Leakage past gasket 16 need never occur if bolts 23 are properly drawn down, and if it should start, can be quickly stopped. Leakage past gasket 11 is, however, not always so easily prevented. Nevertheless, by the construction of Fig. 6, electrolyte leaking past gasket 11 flows over the outer surface of frame 22 and runs off from drip rim 24, without any possibility of its contacting

the edge of plate 6. This plate is therefore completely protected against the destructive effect of electrolysis.

In the modification illustrated in Fig. 8, the cathodic outer retaining wall 31 is flangeless, as more fully described and illustrated in co-pending application Serial No. 597,259, filed June 2, 1945. The upper and lower rims 34 and 35 of wall 31 constitute flat gasket bearing surfaces. The lower rim 34 of wall 31 rests upon gasket 32, which in this case is a flat sheet of resilient material covering the upper bearing surface of frame 22. Similarly, the weight of top member 1 is supported by the upper rim 35 of wall 31, with flat sheet gasket 33 between.

This application is a continuation-in-part of application Serial No. 438,725, filed April 13, 1942, now abandoned.

I claim as my invention:

1. In an electrolytic alkali chlorine cell comprising a cathode assembly including a foraminous structure and cathode electrodes housed in an upright liquid-retaining wall provided with a normally horizontal flat gasket bearing surface all around its lower edge, and an anode assembly co-operative with said cathode assembly including upright anodic electrodes having their lower ends embedded in a slab of low melting metal; the improved support for said cathode and anode assemblies and bottom closure for said retaining wall comprising a flat metal plate extending beneath said retaining wall completely across from side to side thereof and conductively affixed to said slab; a flat, four-sided open frame of impervious electrically non-conducting material intervening between said plate and the cathode assembly conforming with said gasket bearing surface in plan view, and having upper and lower boundary surfaces lying in planes paralleling said gasket bearing surface; a gasket of resilient material between said gasket bearing surface and said frame supporting the weight of the cathode assembly; a drip rim around the lower outer edge of said frame outside and extending downwardly of said plate, protecting said plate against anodic electrolysis in case of leakage of electrolyte past said gasket; a second gasket between said frame and said plate and tension means compressing said second gasket between said frame and said plate; said slab and plate being protected against anodic electrolysis by a layer of impervious electrically non-conducting pressure-plastic material extending around and between the lower ends of said anodic electrodes to said frame and making a sealing bond therewith.
2. In an electrolytic alkali chlorine cell comprising a cathode assembly including a foraminous structure and cathodic electrodes housed in an upright liquid-retaining wall provided with a normally horizontal flat gasket bearing surface all around its lower edge and an anode assembly co-operative with said cathode assembly including upright anodic electrodes having their lower ends embedded in a slab of low melting metal; the improved support for said cathode and anode assemblies and bottom closure for said retaining wall comprising a flat metal plate extending beneath said retaining wall completely across from side to side thereof and conductively affixed to said slab; a flat, four-sided open frame of impervious, electrically non-conducting material intervening between said plate and the cathode assembly, conforming with said gasket bearing surface in plan view, and having upper and lower boundary surfaces lying in planes paralleling said

gasket bearing surface; a gasket of resilient material between said gasket bearing surface and said frame supporting the weight of the cathode assembly, said plate being mortised into the bottom of said frame, leaving said frame extending outwardly and downwardly of said plate to form a drip rim protecting said plate against anodic electrolysis in case of leakage of electrolyte past said gasket; a second gasket between said frame and said plate; and tension means compressing said second gasket between the frame and the plate; said slab and plate being protected against anodic electrolysis by a layer of impervious electrically non-conducting pressure-plastic material

extending around and between the lower ends of said anodic electrode to said frame and making a sealing bond therewith.
